L. SUTKER

ROLLER BEARING FOR SLIDING DOORS

Filed Dec. 16, 1925

Louis Sutker
INVENTOR

BY
Eugene Spindler
ATTORNEY

UNITED STATES PATENT OFFICE.

LOUIS SUTKER, OF BROOKLYN, NEW YORK.

ROLLER BEARING FOR SLIDING DOORS.

Application filed December 18, 1925. Serial No. 75,690.

This invention relates to anti-friction devices such as roller bearings. More particularly, the invention is directed to a sliding door construction having an improved roller bearing upon which the doors are supported, said bearing being especially adapted for slidably mounting the door closure of show and wall cases, and for other similar purposes.

10 Among the objects of the invention is the provision of an improved device of the character described comprising few and simple parts, which shall be easy and cheap to manufacture, durable, and practical and efficient to a high degree.

15 Other objects of this invention will in part be obvious and in part hereinafter pointed out.

The invention accordingly consists in the 20 features of construction, combinations of elements and arrangement of parts which will be exemplified in the construction herein-after described, and of which the scope of application will be indicated in the following 25 claims.

In the accompanying drawing, in which is shown one of the various possible illustrative embodiments of this invention,

Fig. 1 is a cross-sectional view of a fragmentary portion of a show case showing the sliding doors mounted on roller bearings embodying the invention;

Fig. 2 is a fragmentary perspective view showing sliding doors supported on the improved roller bearing;

Fig. 3 is a cross-sectional view taken on line 3—3 in Fig. 2; and

Fig. 4 is a cross-sectional view showing a modified construction of the roller bearing.

40 Referring in detail to the drawing, 10 denotes a fragmentary show or wall case which may be of any well known construction and is seen to include a supporting base 11 having a runway 11^a. A track member 12 is secured to extend through said runway, and door closures 13 and 14 are mounted for sliding movement along said track member 12, said closures preferably being made of plate glass constructed with metallic channel edge-bindings 15. The case 10 is also provided with a top frame 16 having a groove 16^a extending parallel to said runway 11^a, and a partition spacer 17 is fastened in said groove for guiding the upper channel-bound edge portions 13^a and 14^a of

the closures 13 and 14 respectively, as shown in Fig. 1.

The track member 12 and partition spacer 17 may each be of any suitable construction and are here shown to be made of sheet metal 60 of T-shaped cross-section having double-folded central ribs 12^a and 17^a and outwardly extending flanges 12^b and 17^b, respectively, said ribs being adapted to separately guide each door closure in its sliding movement, as 65 will be well understood.

To reduce the wear and sliding friction between the door closures 13 and 14 on the track member 12, a roller bearing 18 embodying the invention is interposed between each lower channel-bound edge 13^b and 14^b of the closures 13 and 14 respectively, and an outwardly extending flange 12^a of the track member 12, as shown in 70 Figs. 1 and 2.

75 Each roller bearing 18 may comprise an elongated channel bar or cage 19 preferably formed of bent sheet metal having a plurality of spaced cylindrical rollers 20 revolvably retained between the parallel side 80 19^a of said cage, said rollers 20 extending through suitable openings 19^b in the cage 19 on which the door closures ride, as shown in Figs. 2 and 3.

85 Each cylindrical roller 20 may have the opposite bases 20^a thereof provided with suitable recesses 20^b adapted to receive indented portions 19^b of the side walls 19^a of the cage 19 for revolvably retaining the rollers in the cage. Said recesses 20^b as 90 here illustrated comprise annular grooves concentrically disposed with relation to the axis of the roller 19 and said indented portion or depressions 19^b may be formed to correspond to said annular grooves as shown 95 in Figs. 1 and 3.

To construct the improved roller bearing 20, the cage 19 is formed by cutting and bending suitable sheet material in the usual manner, the rollers 20 having the annular 100 grooves 20^b are then inserted in proper position between the side walls 19^a of the cage and the portions 19^b simply indented or depressed into the recesses 20^b. The recesses 20^b are preferably made with outwardly flaring sides 20^c so that there is no tendency for the portion 19^a to wedge in the recesses 20^b when depressed therein.

105 It will be noted that the roller grooves 20^a and indentations or depressions 19^b do 110

not normally serve as journal bearings for the rollers but simply guide and retain the latter in proper operative spaced relation, that is to say, the cage 19 and the rollers 20 are in "non-journalized" engagement with each other.

In the improved device, roller bearings 18 are provided, each having two or more rollers 20, and a cage 19 assembled as shown 10 in Fig. 2, the cage being made shorter than the width of the door closure 14. Each closure 14 is adapted to ride on the rollers 20 and on reciprocating said closures the roller bearings 18 will move in the direction 15 of travel of said closures but at a slower velocity as is well understood.

In Fig. 4 is shown a modified, simplified form of the improved roller bearing 28 which is seen to comprise side walls 38^a of 20 the channel cage 38 indented as at 38^b. The latter are adapted to extend into counter-bored recesses 30^b in the ends of an axial passage 30^a of the roller 30.

It will thus be seen that there is provided 25 a device in which the several objects of this invention are achieved, and which is well adapted to meet the conditions of practical use.

As various possible embodiments might be 30 made of the above invention, and as various

changes might be made in the embodiment above set forth, it is to be understood that all matter herein set forth or shown in the accompanying drawing is to be interpreted as illustrative and not in a limiting sense. 35

Having thus described my invention, I claim as new and desire to secure by Letters Patent:

1. In a sliding door construction of the character described, a roller bearing comprising an elongated channel-cage formed of sheet metal, and cylindrical rollers having recessed portions on the plane faces thereof revolvably retained between the side walls of said cage, said walls being indented to 45 extend sufficiently into said recesses for loosely retaining the rollers in the cage. 40

2. In a sliding door construction of the character described, a roller bearing comprising an elongated channel-cage and 50 cylindrical rollers revolvably retained between the side walls of said cage, said rollers having recessed portions with outwardly flaring sides, said walls being indented to 55 extend into said recesses for preventing the separation of the rollers from the cage, whereby the cage is loosely carried by said rollers.

In testimony whereof I affix my signature.

LOUIS SUTKER.
